MULTI-SCIENCE STUDENT TABLE

James W. Cozad, P.O. Box 1069, Taylor, Tex. 76574

Filed Dec. 17, 1965, Ser. No. 219

Term of patent 14 years

(Cl. D16—2)

FIG. I

FIG.2

FIG. 1 is a perspective view of a multi-science student table showing my new design; and

FIG. 2 is a perspective view of a modified form of the table shown in FIG. 1.

The undisclosed side portions of the table are substantially the same as side shown. The undisclosed rear is substantially plane and unornamented.

I claim:

The ornamental design for a multi-science student table, as shown and described.
